UNITED STATES PATENT OFFICE.

AUGUST C. KRAFT AND CHARLES F. MAUERMAN, OF BUFFALO, NEW YORK.

DESIGN FOR A DISPLAY-STAND.

SPECIFICATION forming part of Design No. 27,108, dated May 25, 1897.

Application filed April 8, 1897. Serial No. 631,329. Term of patent 7 years.

To all whom it may concern:

Be it known that we, AUGUST C. KRAFT and CHARLES F. MAUERMAN, citizens of the United States, residing at Buffalo, in the 5 county of Erie and State of New York, have invented and produced a new and original Design for Display-Stands, of which the following is a specification, reference being had to the accompanying drawing, making a part 10 thereof.

This design relates to the configuration of a display-stand, the accompanying drawing being a perspective view of a display-stand embodying our design.

15 The distinctive feature of our design consists in the peculiar shape of the upright or holding portion of the stand and the horizontal or base portion of the stand.

Referring to the drawing, A represents the 20 upright supporting portion of the display-stand, consisting of two backwardly-inclined arms or rods $a\ a$, which are arranged parallel, and an upwardly-curved cross-piece a' , connecting the upper ends of the rods $a\ a$.

B represents the horizontal base portion of 25 the display-stand, consisting of two branches or feet $b\ b$, which extend rearwardly from the lower ends of the upright arms, a cross-bar b' , arranged in rear of the feet, and two ogee or reversely-curved portions $b^2\ b^2$, which connect the rear ends of the feet with the outer 30 ends of the cross-piece, said curved portions diverging rearwardly and outwardly beyond the outer sides of the feet $b\ b$ and forming a rearward enlargement of the base. The central portion of the cross-piece b' is provided 35 with a collar c .

We claim as our invention—

The design for a display-stand, substantially as herein shown and described. 40

Witness our hands this 2d day of April, 1897.

AUGUST C. KRAFT.
CHARLES F. MAUERMAN.
